PHOTOFOLASH CIRCUIT

Stanley D. Eilenberger, Kittredge, Colo., assignor, by
mesne assignments, to Minneapolis-Honeywell Regu-
lator Company, Minneapolis, Minn., a corporation of
Delaware

Application April 10, 1953, Serial No. 347,998

3 Claims. (Cl. 315—192)

This invention relates to improvements in photoflash equipment circuits and more particularly to those which have extension lamps or sidelights for use with a master lamp or flash gun of the battery capacitor type. More specifically, the invention relates to improvements in the type of circuits referred to where the extension lamps or sidelights are to be wired in series. Considerable difficulty has been experienced with present commercial units of this type because it has been the practice to use either self-closing mechanical contacts, which are inherently unreliable and introduce undesirable resistance in the circuit, or to use a so-called "shorting plug" at the terminating lamp.

An object of this invention is to provide a circuit for use in photoflash extension lamps or sidelights which will allow any number of units to be wired in series without the use of special "shorting plugs" or self-closing contacts.

Referring now to the single figure, the part of the circuit left of the line AA represents, by way of example only, the stored energy circuit for the master unit or flash gun where 1 is the primary battery, usually on the order of 22½ to 30 volts, 3 is the energy storage capacitor, the value of which depends upon the voltage of battery 1 and the number of flash bulbs it is desired to fire at once where a nominal value would be on the order of 300 to 500 microfarads. In series with the battery and capacitor is a series charging resistor 2, the value of which is noncritical and a nominal value may be on the order of 1,000 to 3,000 ohms. An operating switch is indicated at 4 which is of the single-pole, single-throw, normally open type. The master lamp is indicated at M and it is in the discharge circuit for the capacitor which will be controlled by the switch 4. The outlet 5 is provided in the discharge or operating circuit for connecting the extension or side lamps.

The extension or side lamps are shown by the part of the circuit to the right of line AA and are connected to the stored energy circuit by plug 7 which will be inserted into outlet 5, said plug 7 having a cord 6 which may be of any desired length, and on its other end is a plug 8 for connection to the first extension lamp.

In the figure there is shown, by way of example, three extension lamps indicated as I, II and III. There may be fewer or more as desired. Each extension lamp hook will be alike and, as shown, there are series outlets 9 and 10 and a terminal or end outlet 11. The series outlets 9 and 10 have one each of their terminals directly connected together. The two remaining terminals are connected together through the flash lamp 12 and connected parallel therewith is the terminal outlet 11.

In connecting the extension lamps together, the plug 8 on the cord 6 coming from the outlet 5 of the stored energy circuit will be connected into the outlet 9 of the first extension lamp I. The second extension lamp II will be connected to the first extension lamp I by a suitable cord 13 having end plugs 14 and 15, with plug 14 being

2

connected into series outlet 10 of extension lamp I and plug 15 connected into series outlet 9 of extension lamp II. Extension lamp III, which is the terminal lamp, will be connected to extension lamp II by a suitable cord 16 having end plugs 17 and 18. Plug 17 will be connected into series outlet 10 of extension lamp II and the plug 18 will be connected into the end or terminal outlet 11 of this terminal extension lamp III.

With the above manner of connection it will be seen that the three extension lamps are now in series circuit with the energy storage circuit. If only one extension lamp is desired, then plug 8 will be inserted into the end or terminal outlet 11 of extension lamp I. If only two extension lamps are desired, then plug 15 of cord 13 will be connected into the end or terminal outlet 11 of extension lamp II. Regardless of how many extension lamps are desired, all except the last will be connected together by their series outlets and this last will be connected to the next to last by its end or terminal outlet 11.

20 The number of extension lamps that can be connected together will depend on the voltage of battery 1. The length of the connecting cords will also have some effect on the number of lamps that can be connected together as the cords have appreciable resistance, although such is not critical. Lengths of cords up to 100 feet have been used with five or six lamps in series.

In commercial use of the extension lamp hookups, the outlets of each will be marked with suitable indicia so one will readily know into which outlet a plug is to be inserted. For example, a suitable marking could be the word "series" for the outlets 9 and 10, and the word "end" or "terminal" for the outlet 11.

With my improved extension lamp hookup it is readily seen that no self-closing contacts or special terminating plug are required. The connecting of extension lamps in series can be quickly and easily accomplished and with no uncertainty involved.

It is not intended that the scope of my invention be limited, except in accordance with the appended claims.

What is claimed is:

1. A photoflash extension lamp unit for connection with a master flash circuit having a source of power, a main flash lamp and a switch for connecting said main flash lamp to said source of power, said extension lamp unit being adapted to be connected directly to said master flash circuit or to another such extension lamp unit to form a series of lamps all connected to said source of power, said extension lamp unit comprising a pair of two terminal outlets having no electrical connection directly between the terminals of each outlet but having one terminal of one outlet connected to the corresponding terminal of the other outlet, an extension flash lamp connected between the corresponding other terminals of said outlets, and a third outlet having two terminals connected across said lamp, the terminals of said third outlet serving as the input terminals to the flash lamp when the lamp unit is the final unit in a series and the terminals of said pair of outlet serving as the "in" and "out" terminals when 40 said extension lamp unit is not the final unit in the series.

2. In a photoflash arrangement: a master flash circuit including a source of power, a main flash lamp, a switch for connecting said main flash lamp to said source of power and an outlet in series with said switch and said source of power; at least three extension lamp units connected to said master flash circuit to be operated simultaneously with said main lamp, each of said extension lamp units comprising a pair of two terminal outlets having no electrical connection directly between the terminals of each outlet but having one terminal of one outlet connected to the corresponding terminal of the other outlet, an extension flash lamp connected between the cor-

3

responding other terminals of said outlets, and a third outlet having two terminals connected across said lamp; and electrical connecting cords having end plugs connecting the units so that the extension lamps are connected in series with said source of power and said switch, one cord extending between said outlet of said master flash circuit and one of the pairs of outlets of the first extension unit in the series, another cord extending between complementary outlets of two extension units, and a further cord extending between one of said pairs of outlets of the next to the last unit in the series and the third outlet of the last unit in the series.

3. In a photoflash arrangement: a master flash circuit including a source of power, a main flash lamp, a switch for connecting said main flash lamp to said source of power and an outlet in series with said switch and said source of power; at least two extension lamp units connected to said master flash circuit to be operated simultaneously with said main lamp, each of said extension lamp units comprising a pair of two terminal outlets having no electrical connection directly between the terminals

of each outlet but having one terminal of one outlet connected to the corresponding terminal of the other outlet, an extension flash lamp connected between the corresponding other terminals of said outlets, and a third outlet having two terminals connected across said lamp; and electrical connecting cords having end plugs connecting the units so that the extension lamps are connected in series with said source of power and said switch, one cord extending between said outlet of said master flash circuit and one of the pairs of outlets of the first extension unit in the series, and a further cord extending between one of said pairs of outlets of the next to the last unit in the series and the third outlet of the last unit in the series.
